FIG. 1

FIG. 2

FIG. 3

Inventor

JOHN M. DOYLE

By *C.B. Birkenbeul.*

Attorney

UNITED STATES PATENT OFFICE.

JOHN M. DOYLE, OF LINNTON, OREGON.

EMBLEM.

Application filed April 28, 1925. Serial No. 26,379.

To all whom it may concern:

Be it hereby known that I, JOHN M. DOYLE, a citizen of the United States, and a resident of Linnton, in the county of Multnomah, 5 and State of Oregon, have invented a new and useful Emblem, of which the following is a specification.

This invention relates generally to the jewelers' art, and particularly to the construction of a collapsible watch charm such as are commonly worn by Masons.

The first object of this invention is the construction of an exceedingly simple and unique form of watch charm or emblem in 15 which the square and compass are the outstanding elements.

The second object is to so construct the charm that it may be closed for the purpose of preventing same from catching on 20 the clothing or other articles.

The third object is to so construct the charm that the letter "G", which forms the central element, will be held in a central position regardless of the particular form 25 in which the compass and square may occupy.

These, and other objects, are accomplished in the manner set forth in the following specification as illustrated in the accompanying 30 drawing, in which:

Figure 1 is a front elevation of the device in its open or extended form of which Figure 2 is a side elevation and Figure 3 is a front elevation showing the charm closed.

Similar numbers of reference refer to the same parts throughout the several views.

Referring in detail to the drawing, which is at a much enlarged scale, the device consists of a compass having a pair of legs 10 40 and a hinge pin 11. A ring 12 is formed integral with one of the legs 10 and is provided with a hole 13 to receive the link 14 by means of which the charm is suspended from a chain or other contrivance.

Between the members 10 is placed a pendant bar 15 having formed near its mid section the letter "G" 16, which is common to articles of this nature. The lower end 17 of the bar 15 is provided with a slot 18 50 through which passes a pin 19 which forms a hinged joint for the arms 20, one of which

is preferably graduated, as shown. The pins 21 pass through the arms 20 and through the legs 10, which are spaced from each other by the washers 22 mounted on 55 the pins 21.

The operation of the charm is as follows: In the form shown in Figure 1 if it is desired to change same to the form shown in Figure 3 it is only necessary to move the 60 points of the compass together under the pressure of the fingers. Since they are held in position only by friction this is very easily done. To reverse their position it is only necessary to separate the compass 65 points.

In some quarters of the globe where the square and compass are sometimes used without the letter "G" this may be omitted, although this omission would rarely be the 70 case.

I am aware that the compass and square and the letter "G" have long been employed together as a Masonic emblem: it is therefore not my intention to cover this combination of 75 elements by themselves, but it is my intention to cover such forms and modifications of same as fall fairly within the appended claims.

I claim:

1. In a charm, the combination of a compass hinged at the union of its legs with a square hinged at the union of its arms and at the intersection of said arms with the legs of said compass.

2. In a charm, the combination of a compass hinged at the union of its legs with a square hinged at the union of its arms and at the intersection of said arms with the legs of said compass; and a pendant bar having formed thereon the letter "G" and having means for holding said letter midway between the legs of said compass.

3. In a charm, the combination of a pair of compass legs hinged at their joined end, one of said legs having a perforated extension formed thereon; a pendant bar between said legs supporting the letter "G" and having its lower end slotted; a square having a hinged joint working in the slot 100 of said pendant bar and having hinged connections to said compass legs adapted to

permit said compass and square to be folded together.

4. In a charm, the combination of a square having its arms joined together by means of a pin; a slotted bar slidably receiving said pin and having thereon a letter "G": a jointed compass having its pivot pin

passing through the upper end of said bar and having its legs hinged to the arms of said compass in a manner that when the said compass is closed it will also close said square and hold said letter "G" in an intermediate position at all times. 10

JOHN M. DOYLE.
